Primary Examiner—Martie Thompson

[57] **CLAIM**

The ornamental design for a combination ball-point pen and lottery number chooser, as shown and described.

DESCRIPTION

FIG. 1 is a front elevational view of the combination ball-point pen and lottery number chooser showing my new design;

FIG. 2 is a rear elevational view thereof;

FIG. 3 is a right view thereof;

FIG. 4 is a left view thereof;

FIG. 5 is a top plan view thereof; and,

FIG. 6 is a bottom plan view thereof.

The numerals depicted by means of broken lines in FIGS. 1 and 2 have been shown for illustrative purposes only and form no part of the claimed design.
